F. W. BROCKSIEPER, OF NEW HAVEN, CONNECTICUT, ASSIGNOR TO SARGENT AND COMPANY, OF SAME PLACE.

Design No. 3,023, dated May 12, 1868.

DESIGN FOR A BRACKET.

The Schedule referred to in these Letters Patent and making part of the same.

TO ALL WHOM IT MAY CONCERN:

Be it known that I, F. W. BROCKSIEPER, of New Haven, in the county of New Haven, and State of Connecticut, have invented a new Design for a Bracket; and I do hereby declare the following, when taken in connection with the accompanying drawing, to be a full, clear, and exact description of the same, and which said drawing constitutes part of this specification, and represents a perspective view.

This invention relates to a design for a wall-bracket, formed from cast metal in imitation of carved wood, the bracket being a large leaf, and the base or support a female figure amidst a cluster of leaves, all as fully shown in the accompanying illustration.

Having described my invention, what I claim as new, and desire to secure by Letters Patent, is—

The design for a bracket, as herein described and illustrated.

F. W. BROCKSIEPER.
